CLOCKCASE

Ludwig Eickemeyer, Union, N. J., assignor to Gibraltar Manufacturing Co., Inc., Jersey City, N. J., a corporation of New Jersey

Application February 4, 1957, Serial No. 44,731

Term of patent 7 years

(Cl. D42—7)

Fig. 2.

Fig. 1.

Fig. 1 is a front elevational view of a clockcase, showing my new design.

Fig. 2 is a top plan view thereof.

Fig. 3 is a bottom plan view thereof.

Fig. 4 is a side elevational view, with a front fragment of the base broken away.

Fig. 5 is a rear elevational view of a major fragment of the design.

The dominant feature of the design resides in the portion shown in full lines.

I claim:

The ornamental design for a clockcase, substantially as shown and described.
